UNITED STATES PATENT OFFICE.

CHARLES RITTENHOUSE, JR., OF CINCINNATI, OHIO.

DESIGN FOR A COMBINED SIGNAL LAMP AND SUPPORTING BRACKET FOR AUTOMOBILES AND OTHER VEHICLES.

Application filed February 3, 1927. Serial No. 20,592. Term of patent 7 years.

To all whom it may concern:

Be it known that I, CHARLES RITTENHOUSE, JR., a citizen of the United States, residing at Cincinnati, in the county of Hamilton and State of Ohio, have invented a new, original, and ornamental Design for Combined Signal Lamp and Supporting Bracket for Automobiles and Other Vehicles, of which the following is a specification, reference being had to the accompanying sheet of drawings embracing two views and forming part thereof.

In said sheet of drawings, Figure 1 is an elevation showing my design and Figure 2 is a fragmentary side elevation of an automobile body showing my design of signal lamp in applied position.

I claim:

The ornamental design for a combined signal lamp and supporting bracket for automobiles and other vehicles, substantially as shown.

CHARLES RITTENHOUSE, JR.
